UNITED STATES PATENT OFFICE

2,350,879

SHOE

Claude H. Daniels, Greenwich, Conn.

Original application August 24, 1934, Serial No. 741,197. Divided and this application October 27, 1937, Serial No. 171,180

3 Claims. (Cl. 36—45)

This invention relates generally to shoes, and particularly to the novel construction of the counter-region. This application is a division of my prior copending application, Serial No. 741,197, filed August 24, 1934, now Patent Number 2,097,451.

In accordance with the usual practice of shoe making the counter, which is a stiffener inserted in the region of the heel to hold up the upper at that point, is inserted between the layers of upper material at the time the shoe is lasted. In other words, the upper is completed and is furnished to the laster, and in accordance with the usual practice the laster loosely inserts the counter between the folds of upper material.

Ordinarily a counter which is generally formed of fiber board, or sole leather, is molded prior to insertion between the folds of upper material so that it conforms generally to the shape of the last and is inserted in this condition between the folds. The presence of a counter of this shape renders it difficult to perforate the various layers of upper material so as to provide a ventilated counter and, furthermore, the respective layers of upper materials are seldom conformed to the shape of the counter so as to present as neat an appearance as if the layers had been pressed together.

It is an object of the present invention, generally stated, to provide a shoe having a built-in counter.

Another object of the present invention is to provide a shoe having a perforated quarter area wherein the perforations extend through the counter stiffener.

Other objects will become apparent to those skilled in the art when the following description is read in connection with the accompanying drawing in which

Figure 1 is a plan view of a double quarter assembly, part being broken away to expose the arrangement of the counter in accordance with the present invention.

Figure 2 is a perspective view of a shoe embodying the quarter assembly shown in Figure 1.

Figure 3 is a plan view of a one piece upper (including vamp and quarter sections) illustrating the application of the present invention in accordance with another embodiment.

Figure 4 is a perspective view of a closed upper formed of the assembly shown in Figure 3 and

Figure 5 is a plan view of a counter stiffener element employed in the embodiment of Figures 3 and 4.

In accordance with the present invention, gen-

erally stated, the usual stiffener, or counter, which is employed in the region of the heel of a shoe, is unified with another upper part before the upper is in condition to be lasted. This may be conveniently accomplished by providing a flat piece of material, such as fiber board, sole leather, or even woven fabric which may be suitably secured, as by adhesive, to the quarter section of a shoe. This may be conveniently accomplished with the materials in a flat condition, since in this condition pressing of the respective layers together so as to cause the respective layers to conform to each other and impart some stiffness thereto is facilitated.

In the event it is desired to perforate the counter, such perforation may be conveniently accomplished with the unified materials in this flat condition and the various layers may be simultaneously perforated. Of course, it will be understood in special circumstances the counter-stiffener, or other upper parts, may be individually preperforated, and thereafter assembled and unified with the perforations thereof in at least partial alignment with the perforations in the other members. Although in such case many of the advantages of the present invention are retained, it is evident that in the usual case it is more economical to unite the respective parts and perforate through all of the assembled parts simultaneously.

In order to conveniently accomplish the building-in of the counter with the upper materials in the flat, it will be understood that the counter stiffener with its adjunct quarter section and lining, if any, may be united before the upper is closed as by vamping or back seaming. However, even with a closed upper which is non-planiform or funnel shaped, it is possible to interpose and unite a counter stiffener in the flat by stretching the closed upper transversely of its opening and thereby flattening the counter area.

Referring now to the drawing, there is illustrated in Figure 1 a section of upper material constituting both quarters of the shoe together in one piece so as to form a seamless-back shoe in a manner familiar to those skilled in the art. The assembly illustrated in Figure 1 may comprise a quarter 1, a lining 2, a counter 3 and a doubler, if desired. The respective layers may be assembled together in the condition shown with the counter centrally situated so as to be properly positioned when the upper is lasted. Each of these parts may be given a coating of adhesive prior to assembly, a suitable adhesive

being vulcanized latex, or nitrocellulose cement. After the parts are assembled together, they may be subjected to pressure so as to flatten the same, and securely adhere them together. If desired, at this time a series of perforations, such as 4, may be conveniently formed passing simultaneously through the three layers so as to produce a shoe which is ventilated at the back.

It will be understood that the lining may form one wall of a counter pocket, or may be dispensed with entirely. In the latter case the counter will be fastened to the outside section directly as by adhesive or stitching.

In assembling the counter with the other parts, the counter may be located so that the upper edge thereof is slightly, say $\frac{1}{4}$ " below the edge of the quarter. When in this position the counter will not interfere with subsequent application of finish strips or binding. The counter may also be located so that the lower edge thereof is above the lower edge of the quarter, as shown in Figure 1. In this manner, although the counter extends far enough to be lasted over, there is no excess material and a compact heel seat results.

As remarked above, the counter as employed in the present invention may be made of the usual materials, such as fiber board or sole leather or it may be made of fabric which has been suitably treated to stiffen it. For instance, a double nap fabric, of good body but depending in weight upon the amount of stiffness desired, may be stiffened as by impregnation with a suitable stiffener such as a starch solution, glue, casein or the like, care being taken to select a stiffener which is compatible with and will permit latex to adhere to the impregnated fabric. The fabric may thus be stiffened to any extent so long as it does not crack when folded flat. When the interstices of the fabric have absorbed sufficient of the stiffener to give the desired stiffness when dry, it is permitted to dry and thereafter a surfacing agent, such as latex, is applied. The latex may be applied by dipping, spraying or brushing and provides a surface to which adhesive will stick. Moreover, the latex and stiffener may be mixed together and concurrently applied. Various textile fabrics may be used, for instance, duck of suitable weight, and mesh fabric, and treated similarly.

The united quarter section 1 with its lining 2 and built-in counter 3 may then be connected with a vamp, the upper being thereby closed. The upper may then be finished in accordance with the usual practice. Thereafter the upper may be assembled with a sole and lasted in the usual manner, but before lasting any of the conforming operations described in said Patent No. 2,097,451 may, if desired, be performed.

After the upper has been lasted the other usual manufacturing operations carried out in the process of making shoes are performed. A shoe made in accordance with the present invention and embodying the counter assembly shown in Figure 1 is illustrated in Figure 2.

In carrying out the invention with separate quarter sections which is the more common practice, the ordinary counter may be cut in two so as to provide half counters 11, as illustrated in Figure 5. One such half counter 11 may be applied to the respective quarters of a shoe, as illustrated in Figure 3 at 11 and 12. In the embodiment illustrated in Figure 3, a one-piece upper 10 is shown, for the purpose of illustration,

wherein both quarters and the vamp are cut from a single piece of leather. It will be understood, however, that the vamp and quarters may be formed separately, if desired, and that the invention as shown and described in connection with a one-piece upper is only for the purpose of illustration.

As shown in Figure 5 the rear edge 13 of the counter 11 is curved corresponding to the general curvature of the usual quarter pattern which is such that when two corresponding sections are fastened together the assembly will assume a cupped or vertically curved shape.

One such counter as 11 may be applied to each 15 quarter of a shoe so that when the quarters are attached together the counters will likewise be fastened together.

The counter 11 which, it will be understood, may conveniently be in a flat condition and may 20 be formed of any suitable material, as stated above, may be secured to one quarter of the shoe and a companion counter 12 may be secured to the opposite quarter. It will be understood that the counters may be interposed between an exterior quarter and the lining 20 therefor, or may 25 be used without a lining, if desired, or with a member large enough to cover it, known as a counter-pocket. Moreover, the counter or stiffener may be applied on the exterior of the quarter 30 in the form of a foxing, or may be covered by a foxing. In accordance with the present invention, however, the counter or stiffener, regardless of the manner in which it is assembled with the other layers, is secured thereto and preferably 35 pressed flat before the upper (in the case of separate quarters) is closed. The upper may then be closed in accordance with the usual practice of closing uppers without the built-in counter, as for instance, in the manner fully described 40 in said Patent No. 2,097,451. After this is accomplished the line of back seam may be covered by the usual backstay 15 which may be applied both inside and out. The upper assembly is then in condition for being assembled with a sole and lasted in the usual manner.

When the quarter, counter and lining are, in accordance with the present invention, unified in the flat, the resultant shoe has an extremely neat appearance in the heel region. Since in accordance with the present invention, the quarter and lining are secured together, as by adhesive, and pressed flat, it is really unnecessary to provide the amount of stiffness which is provided by the ordinary counter which is made of fibre board or sole leather. Indeed, if there is a doubler present, sufficient stiffness may be imparted to the assembly without requiring the use of a counter, and even when a doubler is not present, a piece of woven fabric, such for instance as heavy drill, provides sufficient stiffness for the counter portion of the shoe when constructed in accordance with the present invention. Moreover, a suitable thermoplastic resin capable of being reduced to sheet form may be employed as the stiffener.

From the foregoing description it is apparent that the present invention contemplates the application of a flat counter to an upper, and that the counter is built-in and secured to the upper material during the upper-forming operation before the shoe is lasted. This results in a shoe which is not only of neat appearance but is more comfortable to the foot and conforms more perfectly to the last than one in which a pre-molded counter is provided. Moreover, the procedure of

manufacture is such as to permit ventilating openings to be simultaneously perforated through the various layers in the region of the counter while they are flat. It is to be understood, however, that the respective layers need not be secured together by adhesive, but may be secured together in any other manner, such for instance as by stitching. Moreover, the term "counter" as used herein and in the appended claims is to be understood as descriptive and not in the limitative sense, since it is intended to apply to various materials and in fact to a layer of any suitable material whether applied without or within the quarter section so long as it is secured thereto and provides some stiffness.

When the exterior quarter, the counter and the quarter-lining are adhesively united substantially throughout their entire areas, while in flat condition, and thereafter conformed to the heel end of a last, the bending of the laminated structure about the heel end of the last effects either a condensation of the cell structure in the lining material, or an expansion of the cell structure in the exterior quarter material. This is due to the fact that the radius of curvature for the outside lamina is greater than the radius of curvature for the inside lamina; and since the materials are unified together, they must be bent about the same center. Generally, both condensation in the lining, and expansion in the exterior quarter, will take place to a greater or less extent, depending upon the characteristics of the materials. However, due to the substantially general adhesion between the three layers, the condensation and expansion will be general over the curved area, and not localized where it might exhibit itself as puckers or wrinkles in the lining, or as strains in the exterior quarter. This is a characteristic incident to flatwise unification of the quarter, counter, and lining; which will enable those skilled in the art to identify shoes in which the sections have been unified flatwise; and hence the expression, "said quarter and lining being relatively expanded and condensed about the curved rear portion of the shoe," as used in the appended claims, is to be construed as defining the unique characteristic of shoes in which the quarter, counter, and lining sections have been unified in the flat, before being conformed to the heel end of a last.

Where an exterior leather quarter section and a stiffening element of the counter type are adhesively secured together flatwise throughout substantially their entire engaging surfaces and the flatwise unified composite structure is shaped to form the rear portion of the shoe, the engaging surfaces of the leather quarter section and of the stiffening element, being near the neutral axis and hence substantially free of compression

while the exterior surface of the quarter section is under tension. This results in an improved structure, as heretofore pointed out. The resultant structure is, however, distinctive due to the method of formation.

From the foregoing description it is apparent that many modifications of the shoe and procedure hereinbefore described will present themselves to those skilled in the art without departing from the spirit of this invention. It is to be distinctly understood, therefore, that the invention is not limited to the specific details of structure and procedure described, but that such modifications and the use of such individual features and sub-combinations of features as do not depart from the spirit of this invention are, although not specifically described herein, contemplated by and within the scope of the appended claims.

20 Having thus described the invention, what is claimed is:

1. As a step process article of manufacture an unclosed shoe upper, comprising a flat leather quarter, a flat lining and a flat counter, said counter being adhesively unified with said quarter and lining throughout substantially their entire areas, said composite assembly being flat.

2. As a step product in the manufacture of a shoe, a flat quarter adapted to be conformed to the general shape of the heel end of the last prior to lasting, comprising three layers of material including an exterior quarter section of leather, a stiffening element of the counter type, and an interior lining layer, said three layers being adhesively united throughout substantially the entire areas of their engaging surfaces, the layer which forms the stiffening element being of one piece and having an uninterrupted surface throughout the portion of its area which will form the back of the heel in the completed shoe.

3. As a step product in the manufacture of a seamless back shoe, a flat quarter adapted to be conformed to the general shape of the heel end of the last prior to lasting, comprising a one-piece double exterior quarter section of leather, a one-piece stiffening element of the counter type, a one-piece interior lining co-extensive with said double quarter section, said quarter section, stiffening element and lining being adhesively united throughout substantially the entire areas of their engaging surfaces, said quarter section and lining having substantially uninterrupted marginal portions and uninterrupted surfaces

45 between said marginal portions, and said stiffening element having an uninterrupted surface throughout the portion of its area which will form the back of the heel in the completed shoe.
